Filed Nov. 15, 1961, Ser. No. 67,538

Term of patent 14 years

(Cl. D91—3)

FIG. 1

FIG. 2

FIG. 3

FIG. 4

FIGURE 1 is a side elevation of a bathtub and shower mixing control valve unit, showing my new design;

FIGURE 2 is a fragmentary front perspective view thereof showing the handle in an alternate adjustable position;

FIGURE 3 is a front elevation thereof showing the handle in another alternate adjustable position; and

FIGURE 4 is a rear elevation thereof with portions omitted for convenience of illustration only.

The dominant features of my design reside in the portions shown in full lines.

I claim:

The ornamental design for a bathtub and shower mixing control valve unit, as shown and described.
